[57] CLAIM

The ornamental design for a jewelry link, as shown and described.

DESCRIPTION

FIG. 1 is a perspective view of a jewelry link showing my new design;
FIG. 2 is a top plan view;
FIG. 3 is a side elevation view;
FIG. 4 is a bottom plan view;
FIG. 5 is an end elevational view;
FIG. 6 is an end elevational view opposite the end shown in FIG. 5;
FIG. 7 is a perspective view of the component in a position of use; and
FIG. 8 is a perspective view of the component in a position of use.
The broken line showing of a jewelry chain in FIGS. 7 and 8 is for illustrative purposes only and forms no part of the claimed design.

FIG. 1

FIG. 2

FIG. 3

FIG. 4

FIG. 5

FIG. 6

FIG. 7

FIG. 8
